CLAUDE A. LYON, OF CHICAGO, ILLINOIS, ASSIGNOR TO THE REGAN SAFETY DEVICES COMPANY, INC., OF NEW YORK, N. Y., A CORPORATION OF NEW YORK.

TRAIN-CONTROL SYSTEM.

Application filed May 5, 1926. Serial No. 106,818.

This invention relates to train control systems, and more particularly to roadside apparatus for transmitting one train control indication for freight trains and another and different train control indication for passenger trains under the same roadside conditions.

More specifically, it is the prime desideratum of my present invention to provide a roadside installation for train control systems of the type in which any of a plurality of different signals or indications are transmitted from the roadside to vehicle carried apparatus in response to differing roadside conditions such as "clear", "caution" and "danger" conditions, the said roadside installation being operative for imposing speed or "caution" restrictions for all freight trains to prevent the freight trains from exceeding a permitted speed on down grades, around curves and the like, while permitting a normal or safe running condition of passengers carrying trains.

To the accomplishment of the foregoing and such other objects as will hereinafter appear, my invention consists in the elements and their relation one to the other as herein-after more particularly described; reference being had to the accompanying drawings which show the preferred embodiments of my invention, and in which:

Fig. 1 is a circuit plan view of one form of roadside apparatus embodying the principles of my invention, and

Fig. 2 is a circuit plan view of a modified form of roadside apparatus showing the invention applied thereto.

Referring now more in detail to the drawings and having reference first to Fig. 1 thereof, I show my invention applied to a train control system of the contact or shoe and ramp type in which the indications for controlling the movement of the train are transmitted from the roadside through ramps spacedly positioned along the roadside, with which ramps cooperate a shoe mechanism carried by a vehicle of the train and connected to the vehicle carried circuits. As is well known to those skilled in the art, a plurality of different indications may be transmitted from the roadside to vehicle carried apparatus by controlling the energy supplied to the ramps, and in accordance

with one well-known form of construction indications of the "clear", "caution" and "danger" traffic conditions may be obtained by energizing the ramp with one polarity or another and by deenergizing the same. This is illustrated in Fig. 1 of the drawings by the ramp R located at the controlling station and associated with the roadside signalling apparatus S at such station in a manner to be described presently, the said ramp being energized by a partial circuit comprising the ramp R, conductor 1, the pole changer arm 2, battery B', conductor 3, pole changer arm 4, conductor 5, switch blade 6 operated by movement of the semaphore signal S and conductor 9 connected to one of the rails t, t. The pole changer is connected to so as to be moved by the semaphore signal S so that when the signal is in the 90° or "clear" position the pole changer is in the position shown in full lines in the drawing, with the ramp energized positively, and so that when the semaphore signal is moved to the 45° or "caution" position, the pole changer will be moved with its arms in the dotted line position shown in the drawings so that the ramp is energized negatively. It will be apparent from a consideration of the drawings that when the semaphore arm is moved to the horizontal or deenergized position, the switch blade 6 operated thereby will open the partial ramp circuit to effect the deenergization of the ramp. Thus it will be seen that the operation of the roadside signalling apparatus in response to "clear", "caution" and "danger" conditions will produce in the ramp corresponding traffic controlling indications to be transmitted to the vehicle carried apparatus.

As heretofore stated, the prime desideratum of my present invention centers about the provision of roadside apparatus constructed and designed for transmitting one controlling indication for freight trains and another controlling indication for passenger trains under the same roadside conditions so as to impose different restrictions on freight and passenger trains. To accomplish the desired object, I provide track controlled circuits for controlling the operation of the semaphore signalling apparatus S, the said track controlled circuits includ-

ing mechanism for producing one transmittable indication in the roadside apparatus for trains having a length less than a predetermined length and for producing 5 another and different transmittable indication in said roadside apparatus for trains having a length exceeding the said predetermined length. More specifically, to accomplish the desired end I provide a plurality of insulated track rail sections at a controlling station comprising end sections E' and E² and an intermediate section I insulated from the end sections, the said intermediate section having a predetermined 10 length which is greater than the maximum length of passenger trains and less than the length of a freight train, the construction being such that the bridging of the intermediate section by a freight train produces 15 one indication in the roadside apparatus, while the non-bridging of the intermediate section by a passenger train produces another and different indication in said roadside apparatus.

20 Each of the rail sections E', E² and I is provided with a track circuit energized in the usual way by track batteries located across the rails, the track circuit for the section E' controlling a track relay TC, that 25 for the section E² controlling a track relay TA, and that for the intermediate section I controlling a track relay TB. For convenience of description the length of the intermediate section I may be designated by the 30 arrowed line B and that of the sections E' and E² by the arrowed lines C and A respectively.

35 For effecting the intended results, the track relays TA, TB and TC, governed by the length of a train, combinedly control a circuit means the operation of which is translated to control the operation of the roadside signalling apparatus S, and in the form of construction shown in Fig. 1 of the drawings, 40 the said circuit means comprises a circuit controlling a relay S', the said circuit having the contacts 10, 11 and 12 controlled by the track relays TA, TB and TC, the circuit comprising the battery B², contact 10 normally open, conductor 13, contact 11 normally open, conductor 14, contact 12 normally open, conductor 16, relay S', and conductor 17. The relay S' governs the 45° to 90° operating and holding circuit for the 45 semaphore signal S by means of the contact 18, the said latter circuit comprising the battery B³, conductor 19, contact 18 normally closed, conductor 20, semaphore signalling mechanism S, and conductor 21, the 50 construction being such that when the relay S' is deenergized, the 45° to 90° operating circuit is energized as shown in the drawings and the semaphore signalling arm is in the 90° or normal position and so that when the 55 relay S' is energized the signalling circuit 60

will be opened and the semaphore signalling arm operated to the 45° or "caution" position.

65 It will be apparent from the foregoing that when a freight train moves over the track rail sections, the intermediate section I will be bridged and all of the track circuits TA, TB and TC will be deenergized to close all the contacts in series 10, 11 and 12 for operating the circuit thereof and energizing the relay S', which in turn operates the signalling circuit to move the semaphore signal to its 45° or "caution" position, the moving of the freight train into the section therefore producing a "caution" operation of 70 both the signalling apparatus S and the train control ramp R. It will be further apparent, however, that a passenger train will be permitted to pass the controlling station without operating the roadside apparatus 75 to the "caution" position, the same being maintained in the normal or "clear" indicating position, as shown in the drawings, for the reason that the passenger train being of a length less than that of the intermediate 80 section I, does not effect the simultaneous deenergization of the three track relays TA, TB and TC. By the provision of this construction, therefore, one indication such as a "caution" indication may be transmitted to 85 moving freight trains to impose a restriction thereon and a clear indication may be transmitted to passenger trains moving on the roadbed under the same roadside conditions.

90 Referring now to Fig. 2 of the drawings, I show my invention applied to a roadside controlling apparatus of the induction or non-contact type, the same embodying modified controlling circuits. The induction apparatus may comprise an inductor I' adapted to receive energy from the vehicle carried apparatus for transmitting the same either to an inductor I² or to an inductor I³ depending upon traffic conditions, the selection of the inductors I² and I³ being controlled 95 by pole changer contact arms 22 and 23 connected to for operation by the semaphore signalling apparatus 1^s. The semaphore signalling apparatus is shown in Fig. 2 of the drawings normally in the "caution" or 45° 100 position, and in such position the inductor I' is connected to the inductor I² by means of a circuit comprising the inductor I', conductor 24, pole changer arm 22, conductor 25, inductor I², conductor 26, pole changer 105 contact 23 in full line position, conductor 27, switch arm 28 connected to and movable with the semaphore signal 1^s and conductor 29. When the semaphore signalling arm is operated to the 90° or "clear" position, the inductor I' is connected to the inductor I³ by 110 the shifting of the pole changer arms 22 and 23 to the dotted line positions, the circuit embracing the inductors then including the inductor I', conductor 24, contact arm 22 in 115 120 125 130

dotted line position, conductor 30, inductor I^2 , conductor 31, contact arm 23 in dotted line position, conductor 27, switch blade 28 and conductor 29.

5 In the modification shown in Fig. 2, the signalling arm 1^s is normally in the "caution" position and is maintained in such position by movement of freight trains over the track rail sections, the semaphore sig-

10 nalling arm being moved to the normal or "clear" position by the movement of a passenger train into the sections. To accomplish this operation the rails t, t are divided into insulated sections comprising an intermediate section I and terminal or end sections E' and E^2 similar to those described in connection with Fig. 1 of the drawings, these sections controlling the operation of the track relays TA, TB and TC.

15 20 The track relays TA, TB and TC combinedly control a circuit which includes in series the contacts 32, 33 and 34 arranged in a circuit comprising the battery B^4 , contact 32, conductor 35, contact 33, conductor 36, contact 34, conductor 37, relay S' , conductor 38 and conductor 39 back to the relay B^4 . This circuit is normally open at the contact 33, as shown in the drawings, and is closed only by movement of the passenger

25 30 train over the rails, as when the passenger train is wholly within the intermediate section I. When the circuit is closed, the relay S' is energized for closing a contact 40, which contact operates the 90° operating cir-

35 35 circuit of the semaphore arm 1^s , such latter circuit comprising the battery B^5 , conductor 41, conductor 32, operating mechanism for the signalling arm 1^s , conductor 43, contact 40, conductor 44 back to the battery B^5 .

40 40 Preferably the track controlled circuit which includes the relay S' is provided with stick circuit means for holding said circuit closed until the train leaves the controlling station, said stick circuit means being

45 45 opened by the movement of the train from the controlling station. The said stick circuit means includes a stick contact 45, conductor 46, a contact 47 controlled by track relay TD, conductor 48, battery B^5 con-

50 50 ductors 41, 49 and 38, relay S' , conductor 50 back to stick contact 45. With this construction it will be apparent that when the

55 55 relay S' is closed by the location of a passenger train within the intermediate section I, the relay will be held closed by the stick circuit and will be opened only when the train carried apparatus passes the inductors I^1-I^3 and the train reaches track rail sec-

60 60 tion D which deenergizes the relay TD.

65 65 Still referring to Fig. 2 of the drawings, it will be seen that when a freight train approaches and moves into the control station 1^s it will never lie wholly within the intermediate rail section I so that either the

70 70 track relays TA or TC will be deenergized, maintaining the track controlled circuit to the relay S' open and hence maintaining the signal arm 1^s and its train control inductive means in the "caution" condition. A passenger train, however, under the same roadside conditions will operate the roadside apparatus to the "clear" conditions, permitting unrestricted movement of the passenger train in passing the control station.

75 The use and operation of the roadside control apparatus of my invention will in the main be fully apparent from the above detailed description of the construction and function thereof. It will be further apparent that while I have shown and described my invention in the preferred forms, that many changes and modifications may be made in the structure disclosed without departing from the spirit of the invention, defined in the following claims.

I claim:

1. In a train control system, roadside apparatus for transmitting traffic controlling indications to vehicle carried apparatus, and track controlled circuits controlling the 90 operation of said roadside apparatus for governing the character of indication to be transmitted thereby, said track controlled circuits including mechanism for producing one transmittable indication in said roadside 95 apparatus for trains having a length less than a predetermined length and for producing another and different transmittable indication in said roadside apparatus for trains having a length exceeding the said 100 predetermined length.

2. In a train control system, roadside apparatus for transmitting traffic controlling indications to vehicle carried apparatus, and track controlled circuits controlling the 105 operation of said roadside apparatus for governing the character of indication to be transmitted thereby, said track controlled circuits including mechanism governed by the length of a train for producing one 110 transmittable indication in said roadside apparatus for trains having a length less than a predetermined length and for producing another and different transmittable indication in said roadside apparatus for 115 trains having a length exceeding the said predetermined length.

3. In a train control system, roadside apparatus for transmitting traffic controlling indications to vehicle carried apparatus, track rail sections including an insulated section having a length greater than that of a passenger train but less than that of a freight train, and circuits controlled by said track sections for controlling the operation 125 of said roadside apparatus to govern the character of indication to be transmitted thereby, said track controlled circuits including mechanism for producing one transmittable indication in said roadside appa- 130

- 4
- ratus for passenger trains and for producing another and different transmittable indication in said roadside apparatus for freight trains.
- 5 4. In a train control system, roadside apparatus for transmitting traffic controlling indications to vehicle carried apparatus, and track controlled circuits controlling the operation of said roadside apparatus for governing the character of indication to be transmitted thereby, said track controlled circuits including mechanism for producing a "clear" or "safe" indication in said roadside apparatus for trains having a length less than a predetermined length and for producing a "caution" indication in said roadside apparatus for trains having a length exceeding the said predetermined length.
- 10 5. In a train control system, roadside apparatus for transmitting traffic controlling indications to vehicle carried apparatus, track rail sections including end insulated sections, and an intermediate insulated section having a predetermined length, and circuit means controlled combinedly by said end and intermediate track sections for controlling the operation of said roadside apparatus to produce one transmittable indication in said roadside apparatus for trains having a length less than the predetermined length of the intermediate track section and for producing another and different transmittable indication in said roadside apparatus for trains having a length exceeding the said predetermined length.
- 15 6. In a train control system, roadside apparatus for transmitting traffic controlling indications to vehicle carried apparatus, track rail sections including end insulated sections and an intermediate insulated section having a length greater than that of a passenger but less than that of a freight train, and circuit means controlled combinedly by said end and intermediate track sections for controlling the operation of said roadside apparatus to produce a "clear" indication in said roadside apparatus for passenger trains and to produce a "caution" indication therein for freight trains.
- 20 7. In a train control system, roadside apparatus for transmitting traffic controlling indications to vehicle carried apparatus, insulated track rail sections including end sections and an intermediate section having a predetermined length, a track circuit for each of said track rail sections and circuit means controlled combinedly by said track circuits for controlling the operation of said roadside apparatus, said circuit means being controlled so that the deenergization of all of the track circuits as by the bridging of a train of said intermediate circuit, produces one transmittable indication in said roadside apparatus and the deenergization of less
- than all of said track circuits as by a train having a length less than the length of the intermediate section produces another and different transmittable indication in said roadside apparatus.
- 25 8. In a train control system, roadside apparatus for transmitting traffic controlling indications to vehicle carried apparatus, insulated track rail sections including end sections and an intermediate section having a length greater than that of a passenger train but less than that of a freight train, a track circuit for each of said track rail sections and circuit means controlled combinedly by said track circuits for controlling the operation of said roadside apparatus, said circuit means being controlled so that the deenergization of all of the track circuits as by the bridging of a freight train of said intermediate circuit, produces a "caution" indication in said roadside apparatus and the deenergization of less than all of said track circuits as by a passenger train produces a "clear" indication in said roadside apparatus.
- 30 9. In a train control system, roadside signalling apparatus, roadside apparatus for transmitting traffic controlling indications to vehicle carried apparatus and governed by said signalling apparatus, insulated track rail sections including end sections and an intermediate section having a predetermined length, a track circuit for each of said track rail sections and a circuit controlled combinedly by said track circuits for controlling the operation of said roadside signalling apparatus, said circuit being controlled so that the deenergization of all of the track circuits as by the bridging of a train of said intermediate circuit, produces one indication in said roadside signalling apparatus and the deenergization of less than all of said track circuits as by a train having a length less than the length of the intermediate section produces another and different indication in said roadside signalling apparatus.
- 35 10. In combination, roadside signalling apparatus, insulated track rail sections including end sections and an intermediate section having a predetermined length, a track circuit for each of said track rail sections and a circuit controlled combinedly by said track circuits for controlling the operation of said roadside signalling apparatus, said circuit being controlled so that the deenergization of all of the track circuits as by the bridging of a train of said intermediate circuit, produces one indication in said roadside signalling apparatus and the deenergization of at least one of said track circuits as by a train having a length less than the length of the intermediate section produces another and different indication in said roadside signalling apparatus.

11. In combination, roadside signalling apparatus, insulated track rail sections including end sections and an intermediate section having a length greater than that of a passenger train but less than that of a freight train, a track circuit for each of said track rail sections and a circuit controlled combinedly by said track circuits for controlling the operation of said roadside signalling apparatus, said circuit being controlled so that the deenergization of all of the track circuits as by the bridging of a freight train of said intermediate circuit, produces a "caution" indication in said roadside signalling apparatus and the deenergization of less than all of said track circuits as by a passenger train produces a "clear" indication in said roadside apparatus.
12. In combination, roadside signalling apparatus, and track controlled circuits controlling the operation of said roadside signalling apparatus for governing the character of indication exhibited thereby, said track controlled circuits including mech-
- anism for producing one indication in said roadside signalling apparatus for trains having a length less than a predetermined length and for producing another and different indication in said roadside signalling apparatus for trains having a length exceeding the said predetermined length.
13. In combination, roadside signalling apparatus, track rail sections including an insulated section having a length greater than that of a passenger train but less than that of a freight train, and circuits controlled by said track sections for controlling the operation of said roadside signalling apparatus for governing the character of indication exhibited thereby, said track controlled circuits including mechanism for producing a "clear" indication in said roadside apparatus for passenger trains and for producing a "caution" indication in said roadside apparatus for freight trains.

Signed at Chicago, in the county of Cook and State of Illinois, this 22nd day of April, A. D. 1926.

CLAUDE A. LYON.
